UNITED STATES PATENT OFFICE.

CHARLES C. MORGAN, OF NEW YORK, N. Y., AND GILBERT WRIGHT, OF PITTSFIELD, MASSACHUSETTS, ASSIGNEES, BY MESNE ASSIGNMENTS, TO THE C. C. MORGAN COMPANY, A CORPORATION OF NEW YORK.

TUCKING-MACHINE.

1,128,619.

Specification of Letters Patent. Patented Feb. 16, 1915.

Application filed January 17, 1907. Serial No. 352,827.

To all whom it may concern:

Be it known that we, CHARLES C. MORGAN, a citizen of the United States, and a resident of New York, county and State of New York, and GILBERT WRIGHT, a citizen of the United States, and a resident of Pittsfield, county of Berkshire, State of Massachusetts, have invented a new and useful Tucking-Machine, of which the following is

10 a specification.

This invention involves the provision of a machine for tucking fabrics, and its object is to provide a machine whereby the various operations necessary to form and sew a 15 series of tucks of any desired width and with any desired distance between the stitching of adjacent tucks may be performed properly and automatically with accuracy and rapidity.

20 Prior to this invention it has been customary to form a number of tucks on a piece of fabric by folding the fabric and passing it through an ordinary sewing machine, the operator folding the fabric and guiding it 25 to the needle. To assist the operator in folding the fabric on the proper line and in guiding the fabric accurately as it approaches the needle, what have been called tucking attachments have been provided.

30 Some of these have longitudinal guides against which the operator should cause the fold of the fabric to lie as it is fed toward the needle, the position of this guide being adjustable for different widths of tuck.

35 These attachments have also included an adjustable marker that will, while one tuck is being stitched, mark a line on the fabric at the point where the fold for the next tuck should be made. In all of these so-called 40 tucking attachments, however, the folding and guiding of the fabric is done by hand, so that the speed and the accuracy of the work is dependent upon the individuality of the operator.

45 Generally speaking, it is the object of this invention to provide what may be called a full automatic tucking machine, in the operation of which, the machine being once properly adjusted for a given width of tuck and a given distance between tucks (by which is meant the distance between the 50 stitches fastening one tuck and those fastening the next tuck) a succession of tucks are

accurately formed and sewed without the assistance of the operator except to merely 55 control the starting devices. The machine is arranged so that by pressing a treadle, the sewing machine proper is put into service and the fabric, positively held in proper alinement, is moved relatively to the needle, 60 and by actuating a clutch the mechanism for preparing the fabric for the next tuck is put into operation, continuing until that tuck is positively held in alinement and is ready 65 to be brought to position for the sewing operation, when the preparing mechanism is automatically stopped. The various specific means employed are such that tucks may be produced by unskilled labor that will be more accurate, though more rapidly produced, than those at present made by highly 70 skilled operators, who command high rates of wages. Moreover, tucks may be produced whose cost is almost prohibitive when made by the methods now in use, as for example diagonal tucks crossing other tucks, tapered tucks, etc. It is believed that heretofore no machine has existed in the art 75 which will perform these automatic operations, or any of them.

80 To attain these ends the machine which forms the subject matter of this application performs the following cycle of operations: During the entire sewing operation the fabric is held between longitudinally disposed 85 jaws or clamps which engage both layers of the fabric along a line closely adjacent to that traversed by the needle. The fabric leading to and away from the fabric holder or gripper passes around a longitudinally 90 disposed plate. After one tuck has been formed, the gripper and the plate are so acted upon that the fabric is eventually shifted around the plate with a new portion of the fabric against the edge of the 95 plate and then is again held by the gripper with the line to be sewed away from the edge of the plate. To obtain this operation there is provided in the machine herein illustrated, a table having a sewing machine centrally located thereon; a plate having a thin edge about which the fabric may be folded, and extending longitudinally in front of the sewing machine and at both sides thereof, a longitudinal gripper having 100 105 pressed members which engage the

fabric, means for causing a relative transverse movement of the gripper and the plate to pull the fabric back previous to its transverse shifting and means for gripping the fabric after it has been shifted; means for opening the gripper at the proper time to permit the shifting of the fabric around the plate to be carried on; means for clamping one layer only of the fabric while this operation is proceeding; devices which operate to push the loose portion of the fabric up over and across the plate when the other layer of the fabric is clamped thereby folding the fabric without distortion with a new line at the edge of the plate, and means for automatically feeding the gripper with the fabric through the sewing machine to form the tuck. The width of the tuck and the distance between tucks is adjusted by varying the transverse movement of the gripper relative to the plate or the point at which the devices for opening and closing the gripper are actuated.

As the cycle of operations above outlined, as well as the various means by which such operations are attained, are broadly novel in this art, it is clear that this invention is not limited to any mere details of construction, form or arrangement and that any mere mechanical changes which do not affect the substantial mode of operation of this machine are within the broad invention herein described and claimed.

It should be understood, however, that the invention, in its more specific phase, includes various specific features of construction, arrangement and combination which are deemed preferable, even though it may be possible to avoid their use and still employ the main features of the invention operating to produce substantially the same result by the same general mode of operation.

It should also be understood that there are various features in the machine of this application which are novel independently of whether complete advantage of the full automatic operation be taken, and have distinct and important advantages.

Such features of the machine, which will appear with their incumbent advantages in the course of the following description, co-operate in the specific embodiment of the invention illustrated and described to obtain the full automatic tucking described, but separately involve specific novelty and utility.

Referring to the drawings Figure 1 is a transverse vertical section of one specific embodiment of our invention, this being taken on the line 1—1 of Fig. 2. Fig. 2 is a plan view of the same, a section of the support being the only part of the sewing machine shown. Fig. 3 is a rear view of one end of the machine, being the end at which the preparation of the fabric for sewing a tuck

is effected. Fig. 4 is a transverse section on the line 4—4 of Fig. 3 with the various parts in the position which they occupy after one tuck has been made and the machine is ready to draw the fabric back the proper distance for folding the next tuck. Fig. 5 is a cross-section on the line 5—5 of Fig. 3, some of the parts being omitted in order to make certain operations more clearly appear. This view shows the parts in the position that they occupy after the fabric has been drawn back but before it is released from the gripper. Fig. 6 is a section on the line 6—6 of Fig. 3 with certain of the parts omitted. Fig. 7 is a cross-section on the line 6—6 of Fig. 3 showing a later position of the parts after the gripper has opened and one side of the fabric has been clamped by the plate, the shifting of the fabric about the plate being about to commence. The arrows on Fig. 3 indicate in which direction the various sections of Figs. 4 to 7 inclusive are taken. Fig. 8 is a detail showing the folding device at its normal position. Fig. 9 is a front view partly in section of the mechanism at the rear and at one end of the machine, showing principally the portion shown in Fig. 8. Fig. 10 is a plan partly in section of the cam shaft and other operating parts co-operating therewith. Fig. 11 is a partial front view partly in section of one end of the machine. Fig. 12 (Sheet 1) is a detail showing the needle raising mechanism. Fig. 13 (Sheet 2) is a plan of the bottom plate. Fig. 14 (Sheet 2) is an enlargement of the driving connection for the gripper. Figs. 15 to 19 inclusive are views of the clutch controlling the operation of the fabric shifting devices.

Preceding the more specific description of the various parts of the machine with a general outline of the same, a sewing machine B is carried from a suitable framework A at about the longitudinal center of a table C (see Figs. 2 and 4). The sewing machine is operated by power transmitted to the pulley b^2 , the prime mover not being illustrated. The sewing machine is placed upon the table at right angles to the usual position of a sewing machine upon its work table, that is, instead of feeding the fabric from front to rear of the table or away from the operator, the fabric is fed from one end of the table to the other end thereof. The feeder f^2 (Fig. 2) is, therefore, disposed at right angles to the position which it ordinarily occupies with respect to the table. While the fabric is fed through the machine it lies on the table C passing over a guide tube N and then under and around and over the longitudinally disposed plate D. While being sewed the fabric is engaged by a gripper E which travels along the track c of the table. During the sewing the fabric and the gripper move from the right hand side (Fig. 2) to

the left hand side. After a tuck is sewed the gripper rests on a movable frame or carriage carried by arms K hinged to a fixed shaft I. By operating a lever g or a lever 5 g', a cam shaft H is rotated a single revolution automatically stopping at the end of the revolution, and during this revolution the various moving parts operate to effect the various operations attendant upon a 10 shifting of the fabric around the plate, and upon gripping it once more along the proper line for the sewing operation. The distance between tucks and the width of the tuck is adjusted by adjusting certain of the movements of these parts actuated by the cam 15 shaft. When these operations are completed the gripper and fabric are again moved to the right ready for the next sewing operation, and at the will of the operator 20 the gripper is automatically fed to the needle in synchronism with the ordinary automatic feed of the machine.

The various parts as above stated are all mounted on a suitable support or frame A.

25 B represents a sewing machine of any ordinary type, the machine being driven in the ordinary manner by a belt connecting pulleys b and b' (Fig. 1). In the present instance the machine is intended to be operated by a motor (not illustrated), a belt being connected from the motor to the pulley b².

b³ is a second pulley integrally or rigidly secured to pulley b² so as to revolve with it.

35 When the operator desires to transmit power to the sewing machine proper the treadle B', which is the ordinary type of sewing machine treadle, is pressed downwardly at its rear end, that is, the end which 40 projects under the frame. A pressure on this end of the treadle will, acting through rods B² and b⁴ upon the pivoted lever B⁵ press the opposing faces of pulleys b³ and b' together. A slighter downward pressure on 45 this portion of the treadle will lower the presser foot b⁹ of the sewing machine, this being effected through the rod B², the pivoted bell-crank lever b¹⁰, the rod b¹¹ and the pivoted bell-crank b¹² secured at its forward 50 end to the presser foot bar. The same movement of the bell-crank lever b¹² raises the rod b¹³ which permits the spring stop b¹⁴ to engage the ratchet V of the feed mechanism hereinafter described. When, therefore, the 55 treadle B' has been moved sufficiently to start the sewing machine these various operations have already been accomplished. Another operation that is performed when the rear end of the treadle is moved downwardly is the slight raising of the plate D, in order that the fabric may be easily moved longitudinally during the sewing operation, this being accomplished by the downward movement of the rod u (Figs. 1, 3 and 4) 60 which rocks the shaft u' and so moves up-

ward the rod u² which passes through the table C, engaging the under side of the plate D, this upward movement being opposed by the spring u³.

When the sewing operation has been completed the operator reverses the pressure on the treadle so as to raise the rear end of the treadle. As soon as the pressure on the rear end is reduced the sewing machine is disconnected from the pulleys b³. The reversal of 70 the pressure causes the presser foot to be raised at the same time removing the spring stop b¹⁴ from the ratchet V while the plate D is once more allowed to fall, the rod u² being pressed downwardly by the spring u³. A further operation performed by this movement of the treadle is the setting of the needle at its highest position to permit the fabric to pass under the needle before a tuck is sewed, this being accomplished by a collar b⁶ 75 on the rod B² engaging the pivoted rod b⁶ which raises the rod b¹⁵ (Fig. 12). This rod carries a cross-head b¹⁶ sliding on uprights b⁷ and upon the cross-head are the diverging arms b¹⁷. These arms carry a strip b¹⁸ by springs b¹⁹. When the rod b¹⁵ is moved upwardly the strip b¹⁸ engages a stud b⁸ projecting from the fly-wheel of the machine and so revolves the fly-wheel to bring the stud to its highest position, which position 80 of the fly-wheel is that at which the needle is at its uppermost position.

At any time that it is desired to stop the sewing machine without effecting the other changes, above described, it is only necessary to relieve the pressure slightly on the rear end of the treadle and the machine will stop. By the movement of the treadle, therefore, the operator can adjust the positions of the needle, of the presser-foot, of the ratchet stop and of the plate, and control the actuation of the sewing machine, all in accordance with the particular stage of the work. While the tuck preparing or folding devices are operating, the treadle may 105 be at the neutral position or it may be pressed downwardly at the forward end. When the gripper and fabric are ready to be moved from the left to the right, the forward end of the treadle should be down so that the needle and the presser foot will be up and the ratchet be freely rotatable. When the fabric is to be sewed, passing from right to left, then the rear end of the treadle should be down, lowering the presser foot, 110 placing the stop in engagement with the ratchet and raising the plate from the table to oppose a minimum obstruction to the passage of the fabric while it is being sewed.

The machine illustrated is of suitable size 115 and suitably arranged to make a series of parallel straight tucks for, say, ladies' waists. The fabric during the operation rests upon the longitudinally disposed table C passing under, around the thin edge, and 120

on top of the plate D, which plate is pivotally secured by arms N' to a stud n in front of the table C, the stud being carried on the tube N. There is, therefore, a space at the front of the plate D whereby the fabric may be folded around the plate D (being conveniently inserted by raising the plate as indicated in dotted lines in Fig. 1) and both layers may extend forwardly over the tube N. To explain the mechanism and the operations performed let it be assumed that the parts are in the position shown in Fig. 2, and a tuck is about to be sewed. The fold of the fabric will be held in the gripper E which is in the present instance composed of a number of spring clips E' rigidly held together. In the present instance the plate c, shown separately in Fig. 13, is a continuous plate while the upper portion of the gripper is made up of a number of spring clips acting upon said plate. This gripper is longitudinally disposed, engaging the fabric substantially continuously and on a line closely adjacent to the line traversed by the needle. It rests in a groove or track c which extends from end to end of the machine.

At the rear (right hand) end of the gripper is secured a small plate E² which is bent upward and has at its upper end a slot into which the finger e' projects. This finger is supported upon the cord F which passes around pulleys f, f', the latter being the driving pulley, so that when the cord F is moved to the left (Fig. 2) the gripper is passed to the left carrying the fabric under the needle.

The rate of feed must necessarily be in accordance with the movement for which the sewing machine is designed, that is, it must be in synchronism with the movement of the needle. The ordinary feed of the sewing machine indicated at f² (Fig. 2) is not discarded, but the additional automatic feeding accomplished by the movement of the cord F is made to operate in synchronism with the usual feeding device f². The bent lever v (see Fig. 3) at its upper end passes into the head of the sewing machine and is connected in the machine to the ordinary needle bar operating mechanism, so as to have a rocking movement in synchronism with the movement of the needle operating mechanism. This lever v carries a pawl v' which engages the teeth of the ratchet V. The pawl v' is pivoted to the lever v and at its lower end is connected by a bent rod v² with the ordinary feeder f² of the sewing machine. The movement of the lever v to the left (Fig. 3) moves the ratchet wheel one tooth. When the ordinary feeder f² moves downward it pulls down by means of the rod v² the lower end of the pawl v', lifting it out of the teeth of the ratchet so that it may move back over the ratchet with greater

smoothness, this pulling down being effected just as the lever v is about to move again to the right. As the needle bar and feeding mechanisms of the sewing machine are in synchronism, this construction necessarily causes the movement of the ratchet wheel to be in synchronism with the usual feed mechanism, and therefore the movement of the cord F and the gripper E are in synchronism with said ordinary feeding mechanism. Preferably this additional feed should be connected so that its feeding is a trifle in advance of the ordinary feed of the machine, thus relieving the strain on the latter. One important feature of the invention involves this sewing of the tuck while it is firmly held in alinement by the gripper. Another feature of the invention, which it is advisable to employ, is the feeding of the gripper by the mechanism additional to the usual feeding device of the sewing machine and operating in synchronism therewith. This is advantageous not only because the ordinary feeding device will not always be found strong enough to carry both the fabric and the gripper through the machine, but also because the additional feeding of the gripper, as above described, relieves the strain upon the fabric and also insures the feeding of both layers of the fabric equally through the machine, whereas it has frequently been found in ordinary sewing machines that inferior work is done through an unequal feeding of the upper and lower layers of the fabric.

When the gripper has completed its movement from right to left (Fig. 2) thus finishing one tuck, the finger e' becomes disengaged from the end plate E² of the gripper by means of a cam e² (see Fig. 3) which engages the finger and lifts it out of the slot in the plate E². The gripper and the fabric held by it are now at the left hand end of the machine and the position of the parts at this time is indicated in Fig. 4. The various operations attendant upon preparing a new tuck to be sewed are now to commence. For this purpose power is transmitted to the cam shaft H from the pulley b³ as follows: The pulley b³ drives the pulley b⁴ which is connected by a shaft to the worm B⁵. The worm B⁵ drives the gear B⁶ which is connected to the gears f⁸ by means of a clutch G, one of the gears f⁸ being upon the cam shaft H and driving the same. In order to start these parts in motion the operator holds the handle g which operates the clutch until the moving parts have rotated sufficiently to maintain the clutch in engagement. The arrangement of the clutch is such that after this time it will remain in engagement until it has completed one revolution when it is automatically thrown out of engagement. The parts of the clutch and the description of the same will be set

100

105

110

115

120

125

130

out hereinafter. The clutch may also be manipulated through the handle g' (see Fig. 4) as will also be hereinafter explained.

The revolution of the cam shaft H , which begins when the clutch has been put into engagement, effects a number of movements. One of the first of these is the clamping of the gripper tightly upon its carriage. Thus in Fig. 4 it will be noted that the gripper E 5 rests loosely upon the support E^3 lying in that portion of its track that is formed in the top of said support. The gripper, therefore, was enabled to slide smoothly to the left hand end of the machine during the 10 sewing operation. Once the cam shaft begins to revolve the cam h' moves the lower end of plate spring k^4 rearward. The upper end of this spring engages the rearward end of a longitudinally disposed clamp E^4 15 which is pivotally mounted on pins e^6 so that when the lower end of the plate k^4 moves rearwardly the clamp E^4 swings downward at its forward end upon the lower plate of the gripper and a recessed portion 20 of the clamp engages small vertical studs e^7 on the rear of the lower plate of the gripper. In Fig. 4 the gripper is not clamped, but in Figs. 5 to 7 the gripper is shown clamped in the manner just described. This clamping 25 is effected because during the transverse shifting of the gripper and the fabric, hereinafter described, the movement must be an accurate one and therefore the gripper must be rigidly clamped otherwise the fabric 30 would be moved inaccurately and it would be impossible afterward to engage the fabric accurately along a predetermined line.

As the cam shaft H continues its rotation the gripper carrier gradually swings backward around the axis of the shaft I . This is effected by the movement of the cam h over the roller j which is carried upon the stud J at the end of the link J' mounted upon the shaft I . In Fig. 4 the cam h is 40 shown as so supported by the roller j as to maintain the gripper and its supporting frame in the extreme forward position, but the movement of the cam in the direction of the arrow on shaft H permits the shaft H to gradually fall rearwardly. The cam shaft H is mounted in the three arms K of the gripper supporting frame, which arms are pivoted on the shaft I , and carry the support E^3 for the gripper when it is at the 45 left hand end of the machine. K' is a spring connected at one end to a fixed portion of the base and at its upper end to the shaft K^2 which connects the upper ends of the three arms K . As therefore the cam h rotates, this spring K' acts to move the gripper support on the shaft I as a pivot backward until the position shown in Figs. 5 and 7 is reached. By reference to Fig. 5 50 it will be noted that this movement has been limited by the engagement of the arm

k , which is secured to, and projects downward from, the shaft K^2 , with the lever k' which is pivoted upon the shaft I and extends through the front of the machine. Near the front of the machine there is secured to said lever k' a small projecting pin or stud k^2 which engages the under side of one of the flat keys K^3 , the other end of said key engaging the under side of a downward projection of the table C . The various keys 70 K^3 differ only in their length, the particular key to be chosen depending, for any given width of tuck, upon the distance that it is desired to have between tucks. These keys are therefore adjusting devices for adjusting the distance that the fabric will be pulled when the rearward movement of the gripper is stopped by the arm k . A spring k^3 , connecting the table C and the lever k' , 75 holds said lever in position to receive the 80 end of the arm k and stop the backward movement of the gripper.

The particular key to be chosen depends both upon the distance between tucks and the width of the tuck, since the distance 85 through which the fabric should be shifted transversely before the gripper opens must be such as to allow sufficient fabric for the proper width of tuck and the proper distance between tucks. While the gripper is 90 making this rearward movement, the plate D is also being moved from the position shown in Fig. 4 in which its edge is substantially flush with the edge of the table and forward of the vertical plane in which 95 the sewing is effected, and in which it is held slightly up from the table to the position of Fig. 5 in which it has been moved rearwardly to the other side of the sewing 100 line and has dropped upon the table. This 105 movement irons or smooths the fabric and places the plate in a position to be later engaged by the gripper when the latter again grips the fabric. This movement of the plate is accomplished by the cam h^3 on 110 the cam shaft H . At the beginning of the cycle the plate is held upward by the arm m^2 (Fig. 6) carried by one of the links M' and bearing on the under side of one of the two arms N' . When cam h^3 moves it becomes disengaged from the end of the arm m which is rigidly secured upon the rock shaft M . Shaft M is connected by links M' to studs n carried at the end of the guide tube N which extends the length of the machine and to which is secured by arms N' the plate D . To the arm m is connected a spring m' which has one end fixed to the shaft I and tends to pull the arm downward. When the cam h^3 moves to the left 125 (Fig. 4) the spring m' pulls the arm m downward and causes a slight rocking of the shaft M and therefore a rearward movement of the upper end of the link M' , so carrying the plate D from the position shown in 130

Fig. 4 to the position shown in Fig. 5. This same movement carries downward the arm m^2 from a position supporting one of the arms N' to the position shown in Fig. 6 where the weight of the plate D is carried entirely by the table C . The rearward movement of this plate is limited by the stop or buffer o which is adjusted to different positions according to the width of the tuck that it is desired to sew. As will appear hereinafter, the gripper E is in the present instance always made to close over the fabric and over the edge of the plate D to grip the fabric for a new tuck, when the gripper is at the same point in its reciprocating movement. For this reason the width of the tuck to be sewed may be adjusted by adjusting the distance to which the plate D is moved rearwardly. This adjusting of the stop o is accomplished by movement of arm O which is loosely and slidably mounted on the shaft M and upon which the stop o is carried. From the arm O projects rearwardly a pin o' which may enter any one of a series of recesses of graduated depth in a plate o^2 secured to the front of the table C . The spring l' , acting through the shaft l , arm L , shaft M and arm O , holds the pin in whatever recess it has been placed. During the same period parts of the fabric shifting devices are made to assume a new position preparatory to the operation that brings a new part of the fabric at the edge of the plate. These parts comprise the two arms L which are pivoted upon a shaft L' which shaft is carried upon links L^2 connected to the shaft M . Connecting the arms L is a small shaft l which rests under the arm g' . This arm g' has a cam shaped portion g^2 at its end which is the part pivoted to the shaft I , and the upper part of this cam-shaped portion g^2 engages, when the cam shaft is in the position shown in Fig. 4, a roller h^2 carried on arms h' fixed on cam shaft H . When the cam shaft is moved to disengage the roller h^2 and the cam-shaped member g^2 , then the spring l' which is connected between the shaft l and the flat spring k^4 , before described, comes into action to move the arm L upward from the position shown in Fig. 4 to that shown in Fig. 5. The guide l^2 having a rubber edge l^3 is secured at the upper end of the arms L and is then brought underneath and at the edge of the plate D , as shown in Fig. 5 for a purpose to be hereinafter pointed out.

The shaft L' , constituting the axis for the lever L passes, as shown in Fig. 4, through the arm O and moves transversely with that arm. The advantage gained by this is that the guide l^2 with its rubber edge l^3 is made to assume the same position relative to the plate D regardless of the width of the tuck to be sewed. When, therefore, the movement of the plate is varied by the adjusting devices

above described, the position of the shaft L' upon which the arm L carrying the guide is hinged is correspondingly varied, thus bringing the outer or guide end of the said arm in the proper position relative to the plate. This connection of the shaft L' and lever O also enables the spring l' to hold the pin o' in its proper recess. 70

Preparatory to shifting one layer of the fabric forwardly over the plate D it will be necessary to open the gripper E , but when this is done the other layer of the fabric at one or the other side of the plate must be rigidly held independently of the gripper E in order that the fabric may be as a whole 80 maintained in alinement during this operation. In the present instance this clamping of the fabric preparatory to the folding operation is effected by an electro-magnet P , the circuit to which is automatically closed 85 at the proper instant. The plate D is of magnetic material. The switch controlling the circuit from any suitable source to the coils of the magnet is shown open in Figs. 3 and 5 and closed in Fig. 7. This switch consists of a contact p , in the present instance carried by the support for the gripper, and a contact p' carried on the cam shaft H . Thus in Fig. 5 the operations previously described in detail have taken place, but the 90 plate is not yet attracted by the magnet to clamp the fabric. The cam shaft is moving in the direction of the arrow and the next operation will be the closing of this switch and therefore the energizing of the 100 magnet with the consequent clamping of the fabric as the plate D is attracted to the magnet.

The next operation is the opening of the gripper E . This may occur simultaneously 105 with the clamping of the fabric by the plate D above described. It is effected by the movement of an L-shaped lever Q which is secured to a longitudinally disposed gripper opening bar q . The lower end of this bar 110 q lies above the upper spring jaws of the gripper. The L-shaped lever Q is rigidly secured upon the shaft K^2 and at its lower end engages a cam h^4 on the cam shaft, the end of the lever being held properly against the cam by the spring Q' secured at one end to the lever and at the other end to one of the levers K that support the gripper. When the lower end of lever Q is moved rearwardly by the movement of the cam 115 h^4 the bar q moves downwardly and opens the gripper by raising the upper spring jaws. The relative position of this opener while opening the gripper is shown in Fig. 7, in which figure, however, certain further 120 operations have been performed. At this stage the fabric is still passing under, around and then over the plate D , but a portion of the fabric consisting of the tuck last sewed and a suitable amount of 125 130

fabric on each side of said tuck, the amount of which depends upon the distance desired between tucks, and the width of the tuck, is projecting loosely from the edge of the plate D. The fabric is now in position to have one layer shifted in order that the gripper may take over the fabric at the proper line to hold it during the next sewing operation. In the particular machine 5 illustrated the upper layer is moved forward by a member which engages the under side of the loose end of the fabric and pushes it upwardly over the edge of the plate along the top of the plate. In order 10 to permit this fabric shifter to operate the next step in detail of the machine illustrated is to throw the gripper with its supports still farther rearwardly. This is accomplished by the movement of the shaft 15 K² which has already been described as rigidly connected to the L-shaped lever Q. After the L-shaped lever is moved sufficiently to open the gripper, as above described, a further movement rearward of 20 the lower end of said lever, caused by a further movement of the cam h⁴, will rock the shaft K² far enough to carry the arm h (which has heretofore been described as 25 supporting the gripper after the gripper has first moved the fabric rearward, see 30 Fig. 5) away from the supporting lever k'. When this is effected there is no longer anything to oppose the action of the springs K' which tend to move the gripper frame 35 backward about the axis of the shaft I. Accordingly the gripper and its connecting parts are moved to the position shown in Fig. 7, leaving a wide gap between the plate D and the gripper. To relieve the shock 40 of this movement of the gripper frame there is provided a dash pot R. This is an ordinary air dash pot, the piston R' of which is secured by a link r to the frame A of the machine, while the cylinder R² is 45 pivotally connected at r' with the movable framework that carries the gripper.

The fabric shifter is a longitudinally disposed tube s inclosing a rubber tube s' which is brought out of a slot in the tube to form a rubber edge s². The shifting is effected by the upward movement of this edge s² from the position shown in Fig. 7 obliquely to the right over the edge and on top of the plate D, thus pushing the loose fabric over the edge of the plate to fold it along a new line. The folder or shifter is carried at the lower end of two links s³ (see Figs. 8, 4, 7). These links are pivoted at their upper end upon the longitudinally disposed tube S, 55 which tube is carried at the forward ends of levers S' which are pivoted upon the shaft K² of the gripper supporting frame. The links s³ are connected by an intermediate tube s⁴, while two additional links s⁵ connect 60 the fabric shifter s and the tube s⁴. The

arms S' extend rearwardly of their pivotal point upon the shaft K² being connected by the tube S² (Fig. 7). A flat spring S³ is secured to each arm S' and at its free end engages the folder tending to force the same 70 forwardly toward the table C and plate D. The normal position of the folder and the devices supporting it is indicated in Fig. 4, but in Fig. 8 is shown the mechanism that at this time holds the folder and its supporting devices in this position.

T is a lever pivoted at i upon an arm I' which is fixed upon the fixed shaft I. This lever carries a compound cam on its upper end and at its lower end below its pivotal point it is engaged by the roller h⁵ carried on a crank h⁶ on the cam shaft H. A spring t connected between the fixed arm I' and the lever T above its pivotal point tends to move the upper end of the lever with its compound cam forwardly. This movement is prevented by the engagement of the roller h⁵ with the lower end of the lever T. Upon one of the links s³ (the one shown in Fig. 8) is a recess at s⁶ which in the position shown in Fig. 8, is engaged by a pin t' at the upper end of the lever T. This prevents the links s³ with the folder from moving under the influence of the flat spring S³.

The compound cam carried on the upper 95 end of the roller T will be described with reference to the movement of the lever T and folding devices during the operation of the machine, it being understood that after the tuck has been sewed and the 100 parts are in the position shown in Fig. 4, the shifting devices are held as above explained in the position shown in that figure. When the mechanism has been actuated, as before described, to revolve the cam shaft 105 H, crank h⁶ is moved in the direction of the arrow, (Fig. 8) and the movement of the roller h⁵ upward permits the lever T to move under the influence of the spring t so that the compound cam at the upper end of the 110 lever T moves forwardly and the folder 115 swinging with the links s³ is also carried forwardly under the pressure of the spring S³. This carries the compound cam to such a position as will bring the roller S⁴, which is carried upon one end of the shaft S, above the surface T' of the compound cam on lever T. This movement is not sufficient to cause actual engagement between this roller and said surface. The engagement at a later 120 instant is indicated in Fig. 6, where the roller is partly shown in dotted lines. This engagement of the roller S⁴ and the cam surface T' is caused by the first rearward movement of the shaft K² of the gripper 125 supporting frame, which movement has been heretofore described as due to the rotating of the cam h upon the roller j. Therefore when the gripper moves rearwardly to pull the fabric transversely after a tuck has been 130

sewed, the same movement causes the supports S' of the folding devices to move downward to the position shown in Fig. 6. These fabric shifting devices and their supports remain in the position shown in Fig. 6 until the second movement rearward of the gripper supporting frame, which movement has already been described as being caused by the cam h^4 through the agency of which 10 the arm k is no longer supported on the arm k' . When this movement of the supporting frame takes place, moving the shaft K^2 of said frame rearwardly, the shifting devices are again moved rearwardly and downwardly causing them to assume the position shown in Fig. 7. At this position the folder is in its extreme downward position and the roller S^4 has dropped from the surface T' of the compound cam to the portion of the surface T^2 thereof, (see Fig. 8), dropping over the corner T^2 in its passage. The surfaces T' and T^2 are in alinement, the arms T^4 , which carry the upper surfaces, being bent out to allow a free passage upward of the 25 roller over the surface T^2 . The gripper supporting frame now begins the forward stroke of its reciprocation, being moved forwardly because the cam shaft H has reached such a position as to cause the cam h to begin to rise over the roller j . As this movement continues, carrying the gripper supporting frame forward against the opposition of the springs K' , the folder or fabric shifter is carried forwardly and upwardly. 30 This is due to the fact that the shaft K^2 is moved forwardly carrying with it the arms S' and the folding devices, while the roller S^4 is guided in the proper direction upwardly and forwardly by the surface T^2 of the cam. Referring to Fig. 7, this forward movement assisted by the springs S^8 carries the edge s^2 of the fabric shifter over the guide l^2 with its rubber edge l^8 pushing the fabric over the edge of the plate D and 45 stretching it thereover. The loose portion of the fabric is therefore pushed over and folded ready to be gripped for a new tuck and the shifter or folder holds the fabric until the gripper has again been brought to 50 the proper position to grip the fabric. Before describing the operations to effect the latter purpose, the remaining movements of the folding devices will be described. When the cam shaft H has nearly completed its 55 revolution, the roller h^6 engages the lower surface of the arm T and moves it and its compound cam to the position shown in Fig. 8. This, by the engagement of the pin e' with the recess s^6 , swings the fabric shifting devices upward about shaft K^2 and restores them to the position shown in Fig. 8. The primary purpose of the fabric shifting is that the fabric shall be shifted around the plate the proper distance, but the particular shifter or folder described which en-

gages the fabric from beneath has been found to be peculiarly efficient as its use is not attended with any tendency to strain or distort the fabric.

As soon as the fabric has been pushed over the plate D , as above described, the arm L carrying the guide l^2 is moved back from the position shown in Figs. 5 and 7 to the position shown in Fig. 4 because the cam-shaped portion g^2 of the lever g' is engaged by the roller h^2 on the arm h' of the cam shaft, thus forcing the arm g' to the position shown in Fig. 4 and causing it to press downwardly against the opposition of the spring l' upon the shaft l that connects the arms L .

The further forward movement of the upper support causes the arm k to approach toward the lever k' but, as the L-shaped lever Q is still held with its lower end swung rearwardly by reason of the engagement at this time between said lower end and the portion h^{17} of the cam h^4 , the arm k is inclined rearwardly. When the cam shaft has rotated sufficiently far so that the radial portion h^8 of the cam h^4 passes the lower end of the lever Q , then that lever moves back to the position shown in Fig. 6 permitting the gripper to close. This movement of lever Q is assisted by the spring Q' . The rocking of the shaft K^2 caused by this movement of the lever Q when the latter permits the gripper to close, causes the arm k to swing forwardly so as once more to take a position over the lever k' . The radial portion h^8 of the cam, which governs the closing of the gripper, is so positioned as to permit the closing of the gripper when it has moved to its normal position of Fig. 4. The gripper is now in its extreme forward position and the fabric is folded upon the edge of the plate, the gripper engaging both fabric and plate. Switch p , p' now operates by the further movement of the cam shaft to open the circuit of the magnet and so unclamp the lower layer of the fabric. The plate D is now moved forwardly to assume again its forward and slightly raised position (Fig. 4), this being accomplished because the finger h^8 on the cam shaft engages arm m to raise it and swing the guide tube N forwardly through the medium of the link M' hinged to the shaft M . Finally the movement of the cam h^7 once more permits the gripper clamp E^4 to take the position shown in Fig. 4, so that the gripper is loosened, and may be slid to the right.

The cycle of operations is now completed, the gripper being moved by hand with the fabric embraced by it along the track c from left to right to the position shown in Fig. 2, and, as it is moved, the grooved end plate E^2 of the gripper engages the traveling finger e' and moves it back along the cord F to the position shown in Fig. 2. By now

actuating the treadle B' to put pulleys b', b² into engagement the new tuck is sewed as before.

In the drawings the plate D is shown with its edge lying exactly parallel to the gripper and the line of the sewing. Under these circumstances straight tucks will be produced. If it is desired to produce tapered tucks it is only necessary to adjust the plate so that its edge lies at a slight angle to the line of the sewing. By doing this the fold of the fabric is on the same angle relative to the gripper and the line of the sewing, and a tapered tuck will necessarily result. This adjustment of the plate may be effected by loosening the set screws n⁴ which hold the ends of the plate to the arms N' shifting the end of the plate which is curved for this purpose, and then fastening the plate in an oblique position by again tightening up the set screw.

The details of the clutch G are shown in Figs. 15 to 19 inclusive, the outer member G' of the clutch is rigidly secured to a sleeve G² which revolves loosely upon the fixed shaft I and is rigidly secured to the gear f⁸ mounted upon said sleeve. The inner member of the clutch comprises a ratchet wheel G³ which is secured to revolve with another sleeve G⁴, which is also loosely mounted upon the fixed shaft I and secured to revolve with the worm wheel B⁶.

G³ is a fixed cam secured by screws g⁴ to the supporting frame C' of the table. This cam has a recess g⁵ adapted to receive a roller g⁶ at the end of a rod g⁷ that passes through a slot in the outer member G' of the clutch. This rod carries a ratchet g⁸, which ratchet is normally kept out of engagement with the constantly revolving ratchet wheel G³ by means of the spring g⁹. When the lever g is moved to the left (Fig. 17) it forces the ratchet g⁸ into a tooth of the revolving ratchet wheel and thereby puts the two clutch members into engagement, revolving sleeve G² and gear wheel f⁸ and so the other gears f¹⁰ of the cam shaft. When the outer clutch member G' has moved a short distance the roller g⁶ leaves the recess or notch g⁵ and rides on the periphery of the cam g³. This maintains the clutch in engagement until one revolution has been made and the roller g⁶ again drops into recess g⁵ at which time the clutch becomes automatically disconnected to stop the tuck preparing mechanism. The same result in the present instance can be secured by operating the lever g' whose cam g² engages roller h' and thus moves the cam shaft a sufficient distance to bring the roller g⁶ out of the recess g⁵ and therefore the same operation is effected.

The machine above illustrated and described has been found to satisfactorily and

efficiently achieve the objects set out hereinbefore. It is probable that in many respects the detailed mechanism may be modified, simplified or improved without departing from the essential features of the invention as set forth in the appended claims. It is particularly pointed out that many of the movements herein described are produced in order that two parts shall have a relative movement to each other in order that a desired result may be obtained. In such cases it is not important which of the members has the actual movement. For example, the gripper is moved longitudinally in order that there shall be a relative movement of the gripper and needle to produce the sewing operation while the gripper is positively holding the fabric in alignment. So long as this relative movement is produced it is immaterial which member actually moves, or whether either member is fixed.

Having thus described our invention what we claim as new and desire to secure by Letters Patent is:—

1. In a tucking machine, the combination of means for clamping the fabric longitudinally adjacent to the line of the sewing, a pivotally movable plate adapted to lie between the layers of the fabric, fabric shifting devices, and actuating mechanism connected to said shifting devices to actuate the same automatically.

2. In a tucking machine, the combination of means for clamping the fabric longitudinally adjacent to the line of the sewing, a pivotally mounted plate movable transversely to the line of sewing and adapted to lie between the layers of the fabric, fabric shifting devices, and actuating mechanism connected to the plate and shifting devices to actuate the same automatically.

3. In a tucking machine, the combination of means for clamping the fabric longitudinally adjacent to the line of the sewing, a pivotally mounted plate movable transversely to the line of sewing and adapted to lie between the layers of the fabric, fabric shifting devices, and mechanism for releasing the clamping means and actuating the plate and the fabric shifting devices automatically.

4. In a tucking machine, the combination of a needle, means for feeding the fabric relatively to the needle to form a line of tucking, means for maintaining the fabric clamped during the sewing of said line of tucking, a device for releasing the clamping means after said line of tucking has been formed, fabric engaging devices adapted to present a new fold of the fabric to said clamping means, and actuating mechanism for operating the releasing device and the fabric engaging devices in predetermined relation to each other.

5. In a tucking machine, the combination

- of a needle, means for feeding the fabric relatively to the needle to form a line of tucking, means for maintaining the fabric clamped during the sewing of said line of tucking, means for releasing the clamping means after the line of tucking has been formed, a plate adapted to lie between the layers of the fabric, positively actuated fabric engaging devices adapted to bring a new line of the fabric at the edge of the plate, and actuating mechanism for operating the releasing device, the plate and the fabric engaging devices in predetermined relation.
6. In a tucking machine, the combination of means for clamping the fabric during each sewing operation, a device for releasing the clamping means after each sewing operation, fabric engaging devices adapted to present a new fold of the fabric to said clamping means, actuating mechanism for operating the releasing device and the fabric engaging devices in predetermined relation to each other, and means for adjusting the movement of the fabric engaging devices.
7. In a tucking machine, the combination of means for clamping the fabric during each sewing operation, a device for releasing the clamping means after each sewing operation, a plate adapted to lie between the layers of the fabric, fabric engaging devices adapted to bring a new line of the fabric at the edge of the plate, actuating mechanism for operating the releasing device, the plate and the fabric engaging devices in predetermined relation, and means for adjusting the movement of the fabric engaging devices.
8. In a tucking machine, the combination of means for clamping the fabric during each sewing operation, a device for releasing the clamping means after each sewing operation, a plate adapted to lie between the layers of the fabric, fabric engaging devices adapted to bring a new line of the fabric at the edge of the plate, actuating mechanism for operating the releasing device, the plate and the fabric engaging devices in predetermined relation, and means for adjusting the movement of the fabric engaging devices and of the plate.
9. In a tucking machine, a needle, a longitudinally disposed fabric gripper, means for moving said gripper longitudinally and maintaining the fabric clamped while a line of tucking is sewed by said needle, devices controlling the opening and closing of said gripper, and means for causing said devices to act after the sewing of a line of tucking has been completed.
10. In a tucking machine, a fabric gripper mounted to have a longitudinal movement and a transverse movement, and means for opening and closing said gripper arranged to be actuated during the transverse movement of the gripper.
11. In a tucking machine, a needle, a fabric gripper, means for producing a relative movement between the gripper and the needle in practically the same direction as the line of the tucks and during the performance of the sewing operation, and means arranged to produce a relative transverse movement between the gripper and the needle preparatory to a sewing operation.
12. In a tucking machine, a needle for sewing the tucks, a fabric gripper, means for reciprocating the same relatively to the needle in a direction transverse to the line of the sewing and devices for opening and closing said gripper respectively whenever the same reaches certain predetermined points of said reciprocation.
13. In a tucking machine, a needle for sewing the tucks, a fabric gripper having spring jaws, means for reciprocating said gripper relatively to the needle in a direction transverse to the line of the sewing, and a device for opening said jaws whenever the gripper is at a predetermined position relative to the needle.
14. In a tucking machine, a needle, a fabric gripper, means for reciprocating said gripper relatively to the needle in a direction transverse to the line of the sewing, a device for opening the gripper when it is at a predetermined position relatively to the needle, and means for adjusting the mechanism to vary the relative position at which said opening device acts.
15. In a tucking machine, a needle, a fabric gripper, means for reciprocating said gripper relatively to the needle in a direction transverse to the line of the sewing, and mechanism arranged to open said gripper at one predetermined position of the gripper relative to the needle, and to close said jaws at another predetermined position of the gripper relative to the needle.
16. In a tucking machine, a needle, a fabric gripper, means for reciprocating said gripper relatively to the needle in a direction transverse to the line of the sewing, mechanism arranged to open the gripper at one predetermined position of the gripper relative to the needle and to close said gripper at another similar predetermined position, and means for adjusting the position relative to the needle at which said mechanism acts upon the gripper.
17. In a tucking machine, a fabric gripper, mechanism arranged to move the same longitudinally of the line of the tucks during the sewing operation and mechanism arranged to move the same transversely before the fabric is prepared for each sewing operation.
18. In a tucking machine, a fabric gripper adapted to move longitudinally with the fabric during the sewing operation, means for reciprocating said gripper, mechanism

- for opening and closing said gripper to release and grip the fabric after a tuck has been completed and before another is brought to the needle, and means for adjusting the position of the gripper at which said mechanism opens the gripper. 70
19. In a tucking machine, sewing and feeding mechanism, a longitudinally disposed rocking plate about which the fabric may be folded and mechanism operating upon the same to reciprocate the same transversely. 75
20. In a tucking machine, sewing and feeding mechanism, a longitudinally disposed rocking plate about which the fabric may be folded, a longitudinally disposed fabric gripper and means for causing a relative reciprocation of the gripper and plate. 80
21. In a tucking machine, a longitudinally disposed rocking plate about which the fabric may be folded, a longitudinally disposed fabric gripper, and mechanism connected to both gripper and plate and acting to reciprocate both the gripper and the plate transversely. 85
22. In a tucking machine, a needle, a longitudinally disposed pivotally mounted plate about which the fabric may be folded, a longitudinally disposed fabric gripper, means for causing a relative reciprocation of the gripper and plate, and a device acting upon the gripper to open the same when it is at a predetermined position relatively to the needle of the sewing machine. 90
23. In a tucking machine, a plate about which the fabric is to be folded arranged longitudinally adjacent to the line of the sewing, means for holding the fabric positively in alinement along the line of the tuck during the sewing operation, and means for preventing transverse movement of the fabric at one side of the plate and for simultaneously moving the fabric transversely at the other side of the plate preparatory to the sewing operation. 95
24. In a tucking machine, a plate about which the fabric is to be folded, a table beneath said plate, and an electrical device for varying the pressure between said plate and table. 100
25. In a tucking machine, a needle, a fabric gripper and a plate adapted to receive the fabric, the adjacent edges being normally on opposite sides of a given line, and means for shifting the fabric a given distance to form a new fold to be sewed along the desired line comprising means for moving the fabric gripper in a direction away from the plate, means for opening the gripper at a given point in said movement, devices for pushing the loosened fabric about the plate, means for moving the gripper toward the plate, and means for closing the gripper at a given point in said movement. 105
26. In a tucking machine, a plate disposed to lie between the folds of the fabric, means for causing a relative movement of the fabric and plate during the sewing operation and devices arranged to shift the fabric around the plate and means for causing said devices to act intermediate sewing operations. 110
27. In a tucking machine, a device acting upon the fabric to maintain positive alinement of the tuck during the sewing operation, mechanism for shifting the fabric transversely after the sewing operation, adjusting devices for varying the action of the shifting mechanism, and means for thereafter forming the new tuck to be sewed. 115
28. In a tucking machine, a device acting upon the fabric to maintain positive alinement of the tuck during the sewing operation, mechanism for pulling the fabric transversely after the sewing operation, means for thereafter forming the new tuck to be sewed, and adjusting devices for varying the action of the forming means. 120
29. In a tucking machine, a device acting upon the fabric to maintain positive alinement of the tuck during the sewing operation, mechanism for shifting the fabric transversely after the sewing operation, adjusting devices for varying the action of the shifting mechanism, means for thereafter forming the new tuck to be sewed, and adjusting devices for varying the action of the forming means. 125
30. In a tucking machine, a longitudinally disposed table, a longitudinally disposed plate resting upon the table, and about which the fabric is to be folded, fabric gripping mechanism movable longitudinally, spacing mechanism acting to pull said fabric transversely, and tuck folding or forming mechanism acting to move the fabric at one side of the plate transversely while that at the other side of the plate is rigidly held. 130
31. In a tucking machine, a plate having an edge about which the fabric may be folded, and positively actuated fabric engaging mechanism arranged to move the fabric as a whole a predetermined distance around said plate. 135
32. In a tucking machine, a needle, a fabric gripper and a plate, means for feeding the fabric to form a line of tucking, means for moving the fabric gripper transversely to the line of tucking, means for releasing the fabric from the gripper at an intermediate point in the gripper's movement, fabric shifting devices operating after the gripper has thus released the fabric, and means for causing the gripper to again grip the fabric at another point in the reciprocation. 140
33. In a tucking machine, a plate and a fabric gripper arranged longitudinally with respect to the line of the sewing, means for moving said gripper away from said plate, means for opening said gripper, means for 145

- shifting the fabric around said plate, and means for moving said gripper to said plate and permitting it to close thereover.
34. In a tucking machine, a fabric gripper, means for producing a relative movement between the gripper and the needle of the machine during the sewing operation, a driving means, a clutch connection therewith, a manually operated starter for the clutch, means for automatically opening said clutch when its driven member has moved a definite amount, tuck preparing devices, and mechanism actuated from said driving means to operate said tuck preparing devices. 10
35. In a tucking machine, a fabric gripper, means for producing a relative movement between the gripper and the needle of the machine during the sewing operation, a driving pulley, a clutch connection therewith, a starter for the clutch, means for automatically opening said clutch when its driven member has moved a definite amount, and devices adapted to shift the fabric 20 transversely and prepare a new tuck actuated through the clutch. 25
36. In a tucking machine, the combination with a driving means, a clutch in connection therewith, a starter for said clutch, means for automatically opening said clutch when its driven member has moved a definite amount, tuck preparing devices, and mechanism actuated from said driving means to operate said tuck preparing devices. 30
37. In a tucking machine, a plate about which the fabric may be folded, a fabric gripper in operative relation with the plate, means for varying the angle between said plate and gripper to produce a tuck of varying width. 40
38. In a tucking machine, the combination with the needle of a longitudinally disposed plate adapted to receive the fabric, mechanism connected with the plate and acting to reciprocate the same between a position at one side of the sewing line and a position in which its edge is at the other side of the sewing line, a fabric gripper located to take over the plate and grip the fabric and means to operate said plate and gripper from the same source of power. 45
39. In a tucking machine, the combination of a longitudinally disposed plate about which the fabric may be folded, the sewing machine with its needle located approximately midway the ends of said plate, and means for adjusting the position of the plate to vary the angle between said plate and the line of sewing. 55
40. In a tucking machine, a plate about which the fabric may be folded, a gripper arranged to move the fold of said fabric a predetermined distance from the edge of the plate, and a fabric folder adapted to push 60 the projecting portion of the fabric upward over the edge of the plate.
41. In a tucking machine, a plate about which the fabric may be folded, a gripper arranged to move said fabric a predetermined distance from the edge of the plate, clamping mechanism arranged to act upon one layer of the fabric, and a fabric shifter adapted to push the projecting portion of the fabric upward over the edge of the plate. 70
42. In a tucking machine, sewing means, means for holding the tuck during the sewing, a longitudinally disposed plate adapted to receive the fabric, a table beneath said plate, a movable mounting for said plate adapting it to move transversely and downwardly upon said table, and devices automatically acting upon said mounting. 80
43. In a tucking machine, sewing means, means for holding the tuck during the sewing, a longitudinally disposed plate adapted to receive the fabric, a table beneath said plate, means for lifting the plate from the table, and means for increasing the pressure of the plate upon the table to clamp one 85 layer of the fabric thereto. 90
44. In a tucking machine, a sewing machine and means arranged to feed the fabric therethrough to sew a tuck, and to bring the sewed tuck to a definite position, fabric shifting devices arranged to fold the fabric for a new tuck when it is at said position, and means arranged to actuate the fabric shifting devices when the sewed tuck is at said position. 95
45. In a tucking machine, a fabric gripper and a plate adapted to lie between the layers of the fabric, fabric folding devices, mechanism for giving said plate and fabric gripper transverse movements, each independent of the other, and means for causing the transverse movement of the gripper to move the fabric relatively to the plate. 100
46. In a tucking machine, a fabric gripper mounted to have a transverse movement, gripper opening and closing mechanism, a plate adapted to lie between the layers of the fabric mounted to have a transverse movement, fabric shifting devices, and actuating mechanism connected to the gripper mounting, the gripper opening and closing mechanism, the plate mounting and the fabric shifting devices to actuate each of the same. 110
47. In a tucking machine, a fabric gripper mounted to move longitudinally during the sewing operation, a movable support for said gripper located to receive the same after a sewing operation, a clamp movable to clamp the gripper upon its support, and mechanism connected to the support and to 115 said clamp. 120
48. In a tucking machine, a longitudinally movable fabric gripper, a transversely movable support therefor located to receive the gripper at the end of its longitudinal move- 130

5   56. In a tucking machine, a clamp movable to clamp the gripper to its support, a plate adaptable to lie between the layers of the fabric and mounted to move transversely, a fabric folder adapted to shift the fabric about the plate, a clamping device adapted to clamp one layer of the fabric during the operation of said folder, a gripper opening device, a driven shaft, and actuating connections therefrom 10 to the support, the gripper clamp, the plate mounting, the fabric clamping device, and the gripper opening device.

15   49. In a tucking machine, a longitudinally disposed plate adapted to lie between the folds of the fabric, means for feeding the fabric along the plate during the sewing operation while maintaining the plate in fixed position, and devices for shifting the fabric as a whole around the plate intermediate sewing operations.

20   50. In a tucking machine, a longitudinally disposed plate adapted to lie between the folds of the fabric, means for feeding the fabric along the plate during the sewing operation while maintaining the plate in fixed position, and devices for shifting the fabric around the plate intermediate sewing operations and for moving the plate transversely.

25   51. In a tucking machine, a longitudinally disposed plate about which the fabric may be folded, a fabric gripper in operative relation with the plate, and means for varying the angle between the adjacent edges of the plate and the gripper.

30   52. In a tucking machine, a longitudinally disposed plate adapted to receive the fabric, a table beneath said plate, means for moving said fabric longitudinally of said plate for the sewing operation and transversely for 35 shifting the fold of the fabric, and mechanism moving said plate downwardly and transversely over the table to iron the fabric.

35   53. In a tucking machine, a sewing means 40 a longitudinally disposed plate adapted to receive the fabric, a table beneath said plate, a hinged mounting for said plate arranged to permit the downward and transverse movement of the plate upon the table, and actuating mechanism connected to said 45 mounting.

40   54. In a tucking machine, a fabric gripper mounted to move longitudinally during the sewing operation, a movable support for said gripper located to receive the same 45 after a sewing operation, and actuating mechanism connected to said support to move the same transversely.

45   55. In a tucking machine, a needle a 50 fabric gripper adapted to have a longitudinal movement relative to that of the needle of the machine, a gripper carrier mounted to have a transverse movement, a gripper opening device, and mechanism for actuating the same at a predetermined position of 55 the gripper carrier.

56. In a tucking machine, a fabric gripper adapted to have a longitudinal movement relative to that of the needle of the machine, a gripper carrier mounted to have a transverse movement, a gripper opening 70 device, mechanism for actuating the same at a predetermined position of the gripper carrier, and a longitudinally disposed and transversely movable plate adjacent and parallel to the gripper and located to take 75 into the same at the forward position of the carrier and the rearward position of the plate.

57. In a tucking machine, a fabric gripper adapted to have a longitudinal movement 80 relative to that of the needle of the machine, a gripper carrier mounted to have a transverse movement, mechanism acting upon the gripper to open the same at a predetermined position of the carrier and to close 85 the gripper at the forward position of the carrier, a longitudinally disposed and transversely movable plate adjacent and parallel to the gripper and located to take into the same at the forward position of the carrier 90 and the rearward position of the plate.

58. In a tucking machine, a fabric gripper, mechanism for feeding the fabric gripper longitudinally, means for disconnecting said feeding mechanism operated 95 automatically upon the completion of the sewing operation and means for giving said gripper a transverse movement.

59. In a tucking machine, a fabric gripper, a feeding mechanism, a detachable connection between the feeding mechanism and the gripper, means for detaching said connection dependent upon the movement of the gripper to substantially the end of its travel, tuck forming mechanism and means for operating said gripper and tuck forming mechanism from the same source of power.

60. In a tucking machine, a stitching mechanism, a fabric gripper a table and a plate adjacent thereto, and mechanism acting upon both gripper and plate to move both simultaneously and transversely to pull and iron the fabric.

61. The combination with the needle of a 115 sewing machine, of mechanism engaging and positively clamping the fabric along a line closely adjacent to the line to be sewed during the sewing operation, a longitudinally disposed plate adapted to lie between the layers of the fabric, mechanism for moving said plate from a position with its edge within the clamping means to a position with its edge away from the clamping means and means for operating said clamping mechanism and said plate moving mechanism from the same source of power.

62. In a tucking machine, the combination 120 of a needle, a gripping means, means for preparing a tuck, means arranged to move 125

- said gripping means from one side of said needle to the other, and means arranged to operate said tuck preparing means and said needle from the same source of power.
5. 63. In a tucking machine, the combination of a longitudinally disposed plate about which the fabric may be folded, a fabric gripper mounted to have a transverse movement relatively to said plate, the sewing machine with its needle, and means for adjusting the position of the plate to vary the angle between the edge of said plate and the line of sewing.
10. 64. In a tucking machine, a needle, feeding mechanism, a fabric gripper and a plate adapted to receive the fabric located during the operation of the feeding mechanism on opposite sides of the line of feed, and means acting intermediate sewing operations to move the plate and gripper across the line of feed.
15. 65. In a tucking machine, a plate and a fabric gripper arranged longitudinally with respect to the line of the sewing, means arranged to move the fabric transversely around said plate, devices arranged to move the gripper transversely, and means actuated during the movement of said gripper to open and close the same at different predetermined positions thereof.
20. 66. In a tucking machine, a fabric gripper, clamping the fabric along one side of the line of feed of the machine, a plate arranged to lie between the layers of the fabric and located at the other side of the line of feed, mechanism arranged to move said gripper and said plate independently across the line of feed.
25. 67. In a tucking machine, a needle, a fabric gripper, a plate adapted to receive the fabric, feeding mechanism causing a relative movement of the fabric and fabric gripper with respect to a needle to form a line of stitches, the plate being fixed with respect to the needle during the formation thereof, and means for independently moving the fabric gripper and plate transversely to the line of stitches.
30. 68. In a tucking machine, a fabric gripper and a plate adapted to receive the fabric, feeding means for causing a longitudinal movement of the gripper during the sewing of a tuck while maintaining the plate fixed, and mechanism acting intermediate sewing operations to produce independent transverse movements of the gripper and the plate.
35. 69. In a tucking machine, sewing means, a fabric gripper arranged to clamp the fabric during the sewing operation, means for moving said gripper transversely and to open the same at such a point in its movement as will shift the fabric to the required extent, and means for closing said gripper again upon the fabric at a point determining the width of the tuck.
40. 70. In a tucking machine, sewing means, a fabric gripper arranged to clamp the fabric during the sewing operation, means for moving said gripper transversely and to open the same at such a point in its movement as will shift the fabric to the required extent, means for folding the fabric, and means for closing said gripper again upon the fabric at a point determining the width of the tuck.
45. 71. In a tucking machine, a needle, feeding mechanism, a fabric gripper clamping the fabric along one side of the sewing line during the feeding operation, a plate lying on the other side of the sewing line during the feeding operation, means for moving said gripper backward from the sewing line, and for then opening the same, means for moving said plate across the sewing line, and means for again moving said gripper forward and closing it upon the plate and fabric.
50. 72. In a tucking machine, the combination of a longitudinally disposed plate about which the fabric may be folded, the sewing machine with its needle, and means for adjusting the position of the plate to vary the angle between the edge of said plate and the line of sewing to produce a fold on the fabric at an angle to the line of sewing.
55. 73. In a tucking machine, a fabric gripper, a plate about which the fabric may be folded, means for causing said plate to produce a fold on the fabric at an angle to the line of sewing.
60. 74. In a tucking machine, a plate and a fabric gripper arranged longitudinally with respect to the line of the sewing, means for moving the fabric transversely around said plate, and devices for opening and closing said gripper at different predetermined positions thereof.
65. 75. In a tucking machine, the needle means for producing a relative movement between the needle and the fabric to sew a tuck, a plate adapted to lie between and form the fold of the fabric, and means for adjusting the angle made by the forming edge of said plate and the line of said relative movement to produce a fold on the fabric at an angle to the line of sewing.

In testimony whereof, we have signed our names to this specification, in the presence of two subscribing witnesses.

CHARLES C. MORGAN.
GILBERT WRIGHT.
